UNITED STATES PATENT OFFICE.

CHARLES E. MERRITT, OF SPRINGFIELD, MASSACHUSETTS, ASSIGNOR TO
THE YOST WRITING MACHINE COMPANY.

TYPE-WRITING MACHINE.

SPECIFICATION forming part of Letters Patent No. 448,248, dated March 17, 1891.

Application filed May 16, 1887. Serial No. 238,336. (No model.)

To all whom it may concern:

Be it known that I, CHARLES E. MERRITT, a citizen of the United States, and a resident of Springfield, in the county of Hampden and 5 State of Massachusetts, have invented certain new and useful Improvements in Type-Writing Machines, of which the following is a specification.

My invention in type-writing machines relates more especially to the construction of 10 the type bars or levers and to the means for operating the same, and has for its main objects to simplify and cheapen the machine and improve its mode of operation.

15 To these ends my invention consists in the features of construction and combinations of parts hereinafter more fully described, and particularly pointed out in the appended claims.

20 In the drawings which accompany this specification, Figure 1 is a top plan view of a portion of a type-writing machine involving my improvements. Fig. 2 is a vertical central section taken at the line $x x$ of Fig. 1, 25 with the printing-roller or platen added in dotted lines. Fig. 3 is a detail view, enlarged scale, of a type-bar, its hanger, a push-rod, and a guide for the latter; and Fig. 4 is a bottom plan of a type-bar and its hanger drawn 30 about full size.

In the several views the same part will be found designated by the same numeral or letter of reference.

A represents the bed-plate of the machine, 35 upon which four posts or pillars B are mounted.

C represents the usual top plate or type-circle, supported by said posts or pillars.

E represents the type-bars or type-levers, F the type-basket, and G the platen or print-40 ing-roller.

Each type-bar is journaled or fulcrumed at 1 in a loop or hanger H, which is secured to the top plate C by a set-screw I. The type-bars are formed or provided at their pivoted 45 ends with curved or cam surfaces 2, preferably made broad.

J designates a push-rod, upon the upper end of which rests the convex face of the cam-like portion of the type-bar. The lower end of 50 said push-rod is preferably attached to a socket 4, which is pivoted to one end of a key-

lever 5, that is attached to a post 6, secured to a supporting-plate 7 at the bottom of the machine. At the opposite end of said key-lever is preferably pivoted another socket 8 55 to receive the shank of a stem-key 9, by which the key-lever may be vibrated. The sockets 4 and 8 pass through and are guided by perforations in the bed-plate A. The shank of the stem-key works in a perforation in a cross-bar or bridge 10, coincident with that in the bed-plate through which the socket 8 passes, and thus the stem-key is required to move in a vertical line.

11 designates a perforated ring, which is rigidly supported in the vicinity of the top plate C by knees, flanges, or brackets 12, screwed or otherwise attached thereto. Through the perforations in this ring the upper extremities of the push-rods protrude and bear against the 60 curved surfaces 2 of the type-levers. The holes in the ring 11 and those in the bed-plate through which the sockets 4 pass are preferably arranged in line, so that the push-rods may work in vertical planes.

75 The type-basket is preferably supported by arms 13 13, extending to the posts B B.

In the operation of writing the machine is manipulated in the usual way. As the stem-keys are depressed the push-rods 3 are raised, 80 and they in turn elevate the type-bars, as illustrated at Fig. 3. Upon releasing the stem-keys the type-bars and push-rods drop to their normal positions (indicated at Fig. 1) by reason of the fact that the combined weight 85 of the type-bar, push-rod, socket 4, and rear end of the key-lever exceeds the combined weight of the stem-key, socket 8, and forward end of the key-lever; but, if desired, the weights on each side of the key-levers may be 90 equal and springs employed for returning the moving parts. When the type-bars are at rest within the basket, the upper ends of the push-rods are situated at the lower ends of the curved portions 2 of the type-bars; but as 95 the connecting-rods are being forced up and are elevating the type-bars the curved portions of the latter move over the ends of the push-rods, as indicated by the dotted lines at Fig. 3, and when the type-bars have been lifted 100 to the proper extent to make the impression upon the paper surrounding the platen the

ends of the push-rods will have reached points on said curved surfaces of the type-bars nearer their upper ends and nearer the pivotal points of the type-bars, as seen in the figure last referred to.

It will be observed that the connecting or lifting rods 3 operate upon the type-bars in front of their fulcra and that the power is applied during the full upward stroke of the type-bars.

The key-lever 5 is a lever of the first order and is admirably adapted to a machine in which the type-levers are operated as shown; but so far as one feature of my invention is concerned a key-lever of some other construction or arrangement may be employed, and many other changes in the machine may be made without departing from the spirit of my invention.

Although I have shown and prefer the portion 2 made curved, it may be made straight, the only requirement being that the type-bar shall have a backward bend or hump at its upper end in advance of its fulcrum, by which construction a less movement of the push-rod

is required to elevate the type to the printing-point than is necessary when the lever is made without such bend, and this, it will be understood, is a great desideratum.

What I claim as new, and desire to secure 30 by Letters Patent, is—

1. In a type-writing machine, the combination of a top plate or type-ring, a type-lever depending therefrom and having a cam-surface 2 in advance of its fulcrum, a vertically- 35 arranged detached push-rod, a horizontally-arranged key-lever, and a finger-key.

2. In a type-writing machine, the combination, with a type bar or lever, of a detached push-rod located in front of the fulcrum of 40 said type bar or lever, means for actuating said push-rod, and a device, as 11, for guiding and supporting its upper end, substantially as set forth.

Signed at Springfield, in the county of 45 Hampden and State of Massachusetts.

CHAS. E. MERRITT.
